Fig. 1.

To all whom it may concern:

Be it known that I, Jacobus Adrianus Bergmans, a subject of the Queen of the Netherlands, residing in the city of Waalwijk, Province of Noord Brabant, Kingdom of the Netherlands, have invented a new, original, and ornamental Design for a Shoe, of which the following is a specification, reference being had to the accompanying drawing, constituting a part hereof.

The characteristic feature of my design resides in the folded, upstanding border strip extending completely around the shoe between the sole and the upper in association with single rows of stitching, one row being immediate above the upper edge of the border strip, and the other row being through the border strip along the bottom edge thereof.

I claim:

The ornamental design for a shoe, substantially as shown and described.
